NOZZLE CLAMP

William F. Collins, Westmont, Ill., assignor to
 International Harvester Company, a corpora-
 tion of New Jersey

Application September 22, 1949, Serial No. 117,156

6 Claims. (Cl. 285—108)

1

This invention relates to improvements in clamps and particularly to a pipe clamp. More specifically, the invention concerns a quickly attachable and detachable clamp for securing a spray nozzle or the like to a pipe.

The invention herein is especially applicable to spraying machines involving the use of pipes having a plurality of nozzles at spaced locations thereon for applying weed killing fluids, insecticides and the like to plants.

An object of the invention is to provide a simple and efficient clamp for tightly securing a spray nozzle to a supply pipe.

Another object of the invention is to provide novel clamping means for securing a spray nozzle or jet to a supply pipe wherein the clamp is quickly and easily removed to allow cleaning of the supply pipe and nozzle parts. This is particularly important in a spraying system for insecticides and plant treating fluids because many such treating fluids rapidly contaminate the feed lines, and a great many nozzles must be removed and replaced after cleaning, so that time is an important factor.

Other objects and advantages of the invention will become clear from the following detailed description when read in conjunction with the accompanying drawings wherein:

Figure 1 is an elevation of a section of pipe having a spray nozzle attached thereto by clamping means embodying the features of the present invention;

Figure 2 is a section taken on the line 2—2 of Figure 1; and

Figure 3 is a perspective view of a portion of the clamping structure in the form of a saddle member adapted to be carried by the spray nozzle to straddle the pipe.

In the drawings, the numeral 10 designates an elongated pipe provided with a plurality of orifices at spaced locations lengthwise thereof, one of which is indicated at 11 in Figure 2. Such a pipe forms the boom of a mobile spraying machine adapted for spraying row crops and other vegetation, treating fluid being supplied through the pipe 10 to be released at spaced locations from the pipe through the openings 11. A spray nozzle generally designated at 12 is provided at each of the openings 11 in the pipe to discharge the treating fluid.

As pointed out hereinbefore, a number of different kinds of treating fluids, many of which contaminate the nozzles as well as the pipe and the openings therein, are utilized and discharged from the nozzles 12. Frequent cleaning of the

2

pipes and nozzles is therefore required particularly when changing from one treating fluid to another, and this requires removal and replacement of each individual nozzle from the pipe. The present invention was designed to provide a quickly removable and attachable clamp to facilitate such cleaning.

Nozzle 12 is of generally conventional construction and comprises a threaded pipe portion 13 having a broadened base 14 and a restricted portion 15 adapted for insertion in one of the apertures 11 of the supply pipe. Base member 14 is separated from the pipe by a washer 16 of rubber or the like. Pipe portion 13 is adapted to be received in an opening 17 provided in the transverse bight portion 18 of a generally U-shaped saddle member 19.

The upper end of the pipe 13 is closed by having resting thereupon an insert 20 having a base portion 21 covering the opening at the upper end of pipe 13 and a restricted part 22 extending upwardly and provided with an orifice communicating with the pipe 13. Insert 20 is held in place upon the pipe 13 by a nut 23 threaded upon the pipe 13. Nut 23 further serves to secure the saddle member 19 to the nozzle 12, the bight portion 18 of the saddle member being confined between the base 14 of the pipe 13 and the nut 23.

Saddle member 19 is provided with legs 24 and 25 adapted to straddle the pipe 10 and to engage the sides thereof. One of the legs 25 of the saddle member 19 has a cut-out portion forming a clip or latch part 26 for a purpose hereinafter set forth.

The lower ends of the legs 24 and 25 extend below the pipe 10 on the side thereof opposite the nozzle 12 and at their lower ends are apertured at 27 and 28 to receive an arm 29 of an L-shaped locking member 30 having another arm 31 extending generally at right angles thereto. Arm 29 is adapted for rotation in the openings 27 and 28 in the saddle member on an axis below and spaced from the periphery of the pipe 10 as clearly indicated in Figure 2.

Arm 29, as also clearly shown in Figure 2, is arched or bent, and in the solid line position is in engagement with the pipe 10. In this position the saddle member 19 and the locking member 30 securely hold the nozzle 12 in position on the pipe 10. In this position likewise the arm 31 of the locking member 30 cooperates with the latch element 26 to hold the locking member against rotation and to hold the nozzle or jet securely to the pipe. Saddle member 19 is preferably of spring steel and the latch element 26

bends outwardly slightly to receive the arm 31 and is curved somewhat to hold it in place.

Dismantling and removal of the nozzle from the pipe is accomplished simply by rotating the member 30 using arm 31 as a lever to the dotted line position indicated in Figure 2. The member 30 may then be removed by withdrawing the arm portion 29 of locking member 30 from the apertures 27 and 28 in the saddle. The nozzle 12 may be easily removed and taken apart so that the pipe and the nozzle parts may be cleaned. Replacement then is accomplished very easily and quickly so that spraying may be resumed with a minimum loss of time. Also, due to the arched shape of both of the arms 29 and 31 of locking member 30, either arm may be utilized for insertion in the openings 27 and 28 of the saddle member.

From the foregoing description it should be evident that a novel clamping means has been devised for securing a spray nozzle or the like to a supply pipe. The advantages of such a device become readily apparent when it is realized that a great many nozzles may be attached to a supply pipe at spaced locations thereon for covering as much of an area as possible during spraying.

Having described the invention it should be understood that modifications may be made therein without departing from the spirit of the invention or the scope of the appended claims.

What is claimed is:

1. In combination with a nozzle or the like for attachment to a supply pipe having an opening therein for communication with the nozzle, a U-shaped saddle member carried by the nozzle adapted to straddle the pipe when the nozzle is in registry with the opening therein and having legs apertured at their ends, a latch part carried by the saddle, an L-shaped locking member having one arm extending through the apertures in said saddle and arched to form a cam surface engageable with the surface of the pipe opposite the nozzle, and the other arm serving as a lever for rotating the locking member, said latter arm being cooperable with the latch part to hold the locking member in place.

2. In combination with a nozzle or the like for attachment to a supply pipe having an opening therein for communication with the nozzle, a U-shaped saddle member carried by the nozzle adapted to straddle the pipe when the nozzle is in registry with the opening therein and having legs apertured at their ends, and an L-shaped locking member having an arm extending through the apertures in said saddle and rotatable on an axis spaced from the periphery of the pipe, said arm being bent and rotatable into and out of engagement with the periphery of the pipe to lock the nozzle and saddle assembly to and release it from the pipe.

3. In combination with a nozzle or the like for attachment to a supply pipe having an opening therein for communication with the nozzle, a U-shaped saddle member carried by the nozzle having legs adapted to straddle the pipe when the nozzle is in registry with the opening therein, apertures formed in said legs on a line spaced from the periphery of the pipe opposite the nozzle, a latch part carried by the saddle, an angle member having an arm removably and rotatably

receivable in said apertures and an arm cooperable with said latch part to lock the angle member against rotation, said first mentioned arm having a bent portion forming a camming surface engageable with the periphery of the pipe to secure the nozzle and saddle member thereto in the locked position of the angle member and rotatable to a position with the bent portion spaced from the pipe when it is desired to remove the nozzle and saddle from the pipe.

4. For use with a spray nozzle or the like adapted for attachment to a supply pipe having an opening therein for communication with the nozzle: clamping means for removably attaching the nozzle to the pipe comprising a supporting member secured to the nozzle and having legs adapted to straddle the pipe, a locking member pivotally carried by said legs on an axis spaced from the periphery of the pipe opposite the nozzle, said locking member having a portion rotatable to a position in engagement with the pipe to lock the nozzle and member thereto.

5. For use with a spray nozzle or the like adapted

for attachment to a supply pipe having an opening therein for communication with the nozzle: clamping means for removably attaching the nozzle to the pipe comprising a supporting member secured to the nozzle and having legs adapted to straddle the pipe, a locking member pivotally carried by said legs on an axis spaced from the periphery of the pipe opposite the nozzle, said locking member having a portion rotatable to a position in engagement with the pipe to lock the nozzle and member thereto.

30 35

6. For use with a spray nozzle or the like adapted

for attachment to a supply pipe having an opening therein for communication with the nozzle: clamping means for removably attaching the nozzle to the pipe comprising a supporting member secured to the nozzle and having legs adapted to straddle the pipe, a locking member pivotally carried by said legs on an axis spaced from the periphery of the pipe opposite the nozzle, said locking member having a portion rotatable to a position in engagement with the pipe to lock the nozzle and member thereto, a lever arm on the locking member for rotating the latter, and a latch part carried by the pipe supporting member cooperable with the lever arm to hold the latter in the locking position of the locking member.

40 45

6. For use with a spray nozzle or the like adapted

for attachment to a supply pipe having an opening therein for communication with the nozzle: clamping means for removably attaching the nozzle to the pipe comprising a supporting member secured to the nozzle and having legs adapted to straddle the pipe, a locking member pivotally carried by said legs on an axis spaced from the periphery of the pipe opposite the nozzle, said locking member being arched for rotation into and out of engagement with the pipe and having a portion bent substantially at right angles thereto, said latter portion serving as a lever to rotate the locking member, and means for releasably securing said lever portion to said supporting member when the locking member is in locked position.
